UNITED STATES PATENT OFFICE.

CHARLES H. HELMS, OF POUGHKEEPSIE, NEW YORK, ASSIGNOR TO HIMSELF
AND CHARLES H. GOODSELL, OF SAME PLACE.

HEEL-BURNISHING MACHINE.

SPECIFICATION forming part of Letters Patent No. 396,999, dated January 29, 1889.

Application filed September 20, 1888. Serial No. 285,921. (No model.)

To all whom it may concern:

Be it known that I, CHARLES H. HELMS, a citizen of the United States, residing at Poughkeepsie, in the county of Dutchess and State 5 of New York, have invented new and useful Improvements in Heel-Burnishers, of which the following is a specification.

This invention has for its object to provide novel means for burnishing the heels of boots 10 or shoes; and to such end the invention consists in the features of construction and combination of devices hereinafter described and claimed, reference being made to the accompanying drawings, in which—

15 Figure 1 is a side elevation, partly in section, of a heel-burnisher. Fig. 2 is a plan view of a heel-burnisher.

Similar letters indicate corresponding parts.

In the drawings, the letter A indicates a 20 frame, and B the driving-shaft, shown with a driving-pulley, C, and with pulleys D D, one being fast, the other loose. The counter-shaft E has two pulleys, F F, one fast, the other loose. By shifting a belt (not shown) 25 onto the fast pulleys or onto the loose pulleys the counter-shaft E can be actuated or allowed to come to rest, as may be desired. The counter-shaft E has an eccentric, G, adapted to oscillate the arm H in a horizontal plane 30 about a joint or pivot, I. The oscillatory arm H is supported at its forward end portion by a standard rising from the frame A, and to its front extremity is adjustably secured a burnishing-tool, K. A heater, L, serves to maintain the burnishing-tool properly heated during 35 the operation of burnishing the heel.

In the drawings the heater L is shown in the form of a tube adapted to throw a gas jet or flame against the tool; but of course any 40 suitable well-known heating device can be employed.

A shoe, M, is shown supported by a holder, N. A screw or clamp, O, is shown adapted to clamp or secure a shoe in the holder. As the 45 holder N may be of hard material—such as iron—a guard-pad, P, of soft material—such as leather or rubber—is applied to prevent the tool K from coming into contact with the holder, whereby the tool K might be scratched or injured. A ball, Q, seated in a suitable 50 socket, is shown as supporting the holder N.

By mounting the holder on a ball-and-socket joint the holder can be moved to expose various parts of the heel to the tool K. The stem R of the ball Q is shown as entering a 55 socket in the spring-arm or yielding arm S. A spring, T, tends to force the stem R outward. The stem R being capable of longitudinal motion in the arm S, the holder N can be moved toward or from the arm S, so as to 60 bring the shoe M into position to have the heel properly acted on by the tool K.

The arm S has a connection, U—such as a rod or cord—extending to a treadle or lever, V. By means of the lever V the arm S can be 65 drawn or bent so as to bring the holder N a certain distance away from the burnisher K, so that a shoe can be properly inserted into or taken from the holder. A spring, W, can be applied so as to prevent the arm V exerting 70 such a strain as to break or injure the arm S. I have found it convenient to make the arm S of thin spring metal and firmly securing one end thereof to the frame A by means of a bolt or screw, X. This construction of arm S is 75 simple and cheap, and the spring action of the arm holds the shoe M with its heel in proper contact with the burnisher, while at the same time said spring-arm yields as may be required by various sizes of heels or as may be 80 required to move the holder away from the burnisher while inserting or removing a shoe.

In the drawings the shoe M is shown inserted into the holder with the last still in the shoe. The form of the shoe is thus not apt to 85 be injured, and the clamp or fastening O is able to get a firm hold to securely hold the shoe during the operation. When the shaft E rotates, the eccentric G imparts an oscillating movement to the tool K, so that said 90 tool will effectively burnish the heel. The tool K (shown in the drawings) is of a shape adapted to burnish a curved heel or a heel of the kind commonly called "French heel;" but of course any desirable suitable form of burnisher can 95 be secured to the arm H.

In case the arm S should press the heel too forcibly against the tool K such pressure can be suitably diminished by pressing on the lever V, so as to stretch the spring W sufficiently to relieve the excessive pressure of the arm S toward the tool K without moving the 100

heel out of contact with the tool, whereby the operation might be interrupted.

What I claim as new, and desire to secure by Letters Patent, is—

- 5 1. The combination, with the arm S and the shoe-holder N, connected to the arm by a ball-and-socket joint, of the horizontal arm H, carrying the burnishing-tool, and the shaft E, having the cam G directly engaging the tool-carrying arm and oscillating it in a horizontal plane, substantially as described.
- 10 2. The combination of the spring-arm S, having a socket at one end, a ball, Q, having a stem, R, entering the socket, a spring, T, in the socket acting on the stem, a shoe-holder, N, jointed on the ball, a lever, V, connected with the spring-arm, the horizontal arm H, carrying the burnishing-tool, and the shaft E, having the cam G for oscillating the tool-carrying arm in a horizontal plane, substantially as described.
- 15 3. The combination, with the frame A and

the shoe-holder N, of the driving-shaft B, the counter-shaft E, located above the driving-shaft and having the cam G, and the horizontal arm H, having a burnishing-tool, K, and directly engaged by the cam and oscillated in a horizontal plane by said cam, substantially as described. 25

4. The combination of the frame A, the spring-arm S, rigidly secured at one end, the shoe-holder N, connected with the spring-arm by a ball-and-socket joint, the pivoted lever V, and the spring W, connecting the lever with the spring-arm, with the oscillating burnishing-tool K, substantially as described. 30 35

In testimony whereof I have hereunto set my hand and seal in the presence of two subscribing witnesses.

CHARLES H. HELMS. [L.S.]
